UNITED STATES PATENT OFFICE.

THOMAS F. HATHAWAY, OF ELGIN, ILLINOIS, ASSIGNOR TO ILLINOIS WATCH CASE COMPANY, OF ELGIN, ILLINOIS, A CORPORATION OF ILLINOIS.

CONVERTIBLE WATCHCASE.

1,139,416.

Specification of Letters Patent. Patented May 11, 1915.

Application filed December 4, 1914. Serial No. 875,490.

To all whom it may concern:

Be it known that I, THOMAS F. HATHAWAY, a citizen of the United States, residing at Elgin, in the county of Kane and State of Illinois, have invented certain new and useful Improvements in Convertible Watchcases, of which the following is a specification.

The present invention relates to a watch case so designed and arranged as to be readily, easily and quickly converted from the wrist type of watch to the belt or chatelaine type.

The objects of the present invention are to provide oppositely disposed swiveled mountings for attaching the ends of a chain or bracelet to the watch case whereby it is given the style and appearance of a wrist watch, and by the provision of such swivel mountings the watch case is capable of being turned over whenever desired without twisting the chain or bracelet, so that the watch may lie face downward upon the wrist of the wearer, thus keeping the crystal from being accidentally struck against surfaces which might shatter it, and also permit the display of any engraving, or inlay or other ornamental design on the back of the watch.

A further object is to arrange one of said swiveled mountings in a manner whereby the bow connecting the bracelet or chain with said mounting may be readily and easily disconnected therefrom, when said bow is turned into a certain position, which position is not assumed while the watch is being worn by the wearer.

A further object is to give to the above mounting from which the bow is detachable, a form and configuration whereby when said bow is disconnected the watch assumes the appearance to all practical purposes of the ordinary belt or chatelaine type of watch.

The invention further consists in the features of construction and combinations of parts hereinafter described and claimed.

In the drawings: Figure 1 is a perspective of the watch case of the present invention when used as a wrist watch; Fig. 2 is a face view of said watch case when used as the chatelaine or belt type of watch; Fig. 3 is an enlarged detail of that end of the watch case to which the detachable bow of

the chain or bracelet is connected, showing 55 in dotted lines the position assumed by the bow while the watch is being worn on the wrist of the wearer and in full lines the position in which the bow must be placed in order to detach it from the watch case; 60 Fig. 4 is an enlarged detail of the detachable bow and the member on the watch case to which it is joined; Fig. 5 is a bottom plan view of the bow shown in Fig. 4, showing 65 the flat faces of the pintles thereon; and Fig. 6 is an elevation of the knob or stem attached to the watch case and to which the detachable bow is joined.

In the art to which the present invention relates, two characteristics have been found 70 to be necessary or desirable in connection with wrist watch cases. The first is, that the connection between the watch case and chain or bracelet, should be of the swivel type in order that the watch may be readily 75 turned to expose the face or back thereof without removing the same from the wearer, or without twisting the chain or bracelet. The second point is that at least one of the members on the watch case to 80 which one end of the chain or bracelet is attached should be of such character as to permit of the bracelet or chain being removed and the watch used as the chatelaine or belt type, without it being readily discernible that it was intended as a watch of 85 the wrist type variety. Owing to the fact that it is not always desirable to wear the watch as a wrist watch, it is frequently necessary for the user to possess two watches, 90 one of the wrist variety, and one of the belt or chatelaine variety, the reason being that the members on the watch case of the wrist watch to which the ends of the chain or bracelet are attached, are of such a nature 95 that if the watch were used as a chatelaine or belt watch, the watch case would not present the usual appearance of the belt or chatelaine type of watch, and it would be apparent that the watch was intended for 100 use as a wrist watch, and had been converted to a use other than that intended.

In the present invention, the watch case is so designed and arranged, that although perfectly feasible and practical for use as a 105 wrist watch, it can, nevertheless, be used as a chatelaine or belt type of watch without any body detecting that the watch was be-

ing used in a manner other than which it was intended to be.

Referring to the drawings, and particularly Fig. 1, the device as there illustrated, 5 consists of a watch case 7 provided at one end with the usual stem and crown 8 and pendant 12, and provided at its other end with a knob or protuberance 9.

As shown in Fig. 1, the watch is intended 10 for use as a wrist watch and when so used a chain or bracelet 10 of suitable construction is employed which carried a bow 11 at one end attached to the pendant 12, which latter is swivelly mounted. A bow 13 is carried 15 by the other end of the chain 10, which bow is similar in general appearance to the bow 11, and each of the bows are made of a suitable spring metal. The bow 13 is formed with inwardly extending pintles 14, which 20 are adapted and arranged to seat within recesses 15 formed in the knob or protuberance 9, and said protuberance is formed with oppositely disposed grooves 16 which extend from the recesses 15 to the cross groove 17 25 formed at right angles or approximate right angles to the grooves 16. By the provision of these slots or grooves 16 and 17, the lip overhanging the recesses 15 is cut away or reduced at the points of location of the 30 grooves 16, and an arrangement is therefore provided, so that the pintles 14 on the bow may be easily and readily pulled out from the recesses 15 when the bow is turned so as to bring the pintles 14 into alinement with 35 the grooves 16. It is thought this will be clearly understood by referring to Figs. 3 and 4. From the above it will be seen that retraction or separation of the bow from the protuberance 9, can only be effected by turning 40 the bow so as to bring the pintles 14 into alinement with the grooves 16, that is the bow must be turned into a certain predetermined position before it can be removed. The grooves are so formed in the construction 45 shown that the bow would have to be turned approximately at right angles to the position it ordinarily assumes on the wearer, in order to enable separation of the bow from the protuberance, such position could 50 not be assumed while the watch is upon the wearer unless placed so by intent and therefore a separation can only be had by a desire of the user and by his deliberately placing the parts in a position to make the separation 55 possible. The bow 11, can, of course, be left on at all times, and need not be readily separable, since such bow is employed with the chatelaine or belt type of watch as well as with the wrist variety. 60 When the bow 13 is disconnected in the manner above stated, and the chain or bracelet 10 removed, it is obvious that a watch is produced which save for the small protuberance 9, is of the design ordinarily 65 employed in the chatelaine or belt type of

watches. The protuberance 9 is not of such nature and size as to indicate that the watch was one designed solely for the wrist use after the chain or bracelet is removed. Thus by this simple construction a watch case is 70 produced, which can be readily converted from the wrist variety to the chatelaine or belt variety, or vice versa and at the same time have the appearance of the ordinary wrist watch or chatelaine or belt watch, as 75 the case may be. Each of the bows 11 and 13 being of similar size and style the watch case is well balanced and of symmetrical appearance when used as a wrist watch.

I claim:

1. A watch case having a pendant on one side thereof adapted to receive a bow, a protuberance on the opposite side thereof, a second bow, said protuberance having sockets 85 formed therein to receive the pintles of said second bow, and said protuberance being configured to permit withdrawal of said pintles from engagement therewith when said second bow is turned into a predetermined position, substantially as described. 90

2. A watch case having a pendant on one side thereof adapted to receive a bow, a protuberance at the other side thereof, a second bow, said pendant and protuberance being swivelly mounted upon said case, recesses in said protuberance adapted to receive the pintles of said second bow, and said protuberance being configured to permit removal of said second bow therefrom when said second bow is turned into a predetermined position, substantially as described. 95

3. A watch case having a pendant on one side thereof adapted to receive a bow, a protuberance on the opposite side thereof, a second bow, recesses in said protuberance to receive the pintles of said second bow, oppositely disposed grooves leading from the outer edge of said protuberance to said recesses whereby said pintles can be withdrawn from said protuberance only when said second bow is turned to aline said pintles with said grooves, substantially as described. 110

4. A watch case having a pendant on one side thereof adapted to receive a bow, a protuberance in the form of a ball on the other side thereof, a second bow, recesses in said protuberance for receiving the pintles of said second bow, oppositely disposed grooves 120 extending from the outer edge of said protuberance to said recesses and forming passages to permit withdrawal of the pintles from the protuberance when said bow is turned to aline said pintles with said grooves, substantially as described. 125

5. A watch case having a pendant on one side thereof adapted to receive a bow, a protuberance on the other side thereof, a second bow, wedge shaped pintles extending 130

from said second bow, recesses in said protuberance for receiving said pintles and said protuberance having oppositely disposed grooves leading from said recesses to the 5 outer edge of said protuberance whereby said pintles may be withdrawn from said protuberance by turning said bow to aline

said pintles with said grooves, substantially as described.
